(57) **CLAIM**

The ornamental design for a data input device, as shown and described.

DESCRIPTION

FIG. 1 is a perspective view of the data input device of the present invention;

FIG. 2 is a left side view of the data input device shown in FIG. 1;

FIG. 3 is an elevational top view of the data input device shown in FIG. 1;

FIG. 4 is a right side view of the data input device shown in FIG. 1;

FIG. 5 is an elevational bottom view of the data input device shown in FIG. 1;

FIG. 6 is an elevational rear view of the data input device shown in FIG. 1; and,

FIG. 7 is an elevational front view of the data input device shown in FIG. 1.
